No. 721,891.

PATENTED MAR. 3, 1903.

G. A. HERMANSON.
AUTOMATIC COUPLING.
APPLICATION FILED JAN. 3, 1903.

NO MODEL.

UNITED STATES PATENT OFFICE.

GUSTAF A. HERMANSON, OF CHICAGO, ILLINOIS, ASSIGNOR TO JAMES MUNTON, OF MAYWOOD, ILLINOIS.

AUTOMATIC COUPLING.

SPECIFICATION forming part of Letters Patent No. 721,891, dated March 3, 1903.

Application filed January 3, 1903. Serial No. 137,655. (No model.)

To all whom it may concern:

Be it known that I, GUSTAF A. HERMANSON, a citizen of the United States, residing in Chicago, in the county of Cook and State of Illinois, have invented a new and useful Improvement in Automatic Couplers, of which the following is a specification.

My invention relates to automatic car-couplers for railway-cars of the class commonly known as "Master Car-Builders' couplers," and which have a forked draw-head, a pivoted knuckle, and gravity-lock.

The object of my invention is to provide a car-coupler of a simple, efficient, strong, and durable construction in which the lock will be prevented from creeping or jumping upward, in which the lock may be set to couple or uncouple, which will have means for preventing the removal of the lock from the draw-head, and in which the lock will be readily raised to uncouple in case the draft-rigging of one coupler should break or accidentally become disengaged from its car, so that the detached coupler may be supported by the lifting lever and chain, and thus prevent its dropping down upon the track.

My invention consists in the means I employ to accomplish this object or result—that is to say, it consists in the novel construction of parts and devices and in the novel combinations of parts and devices herein shown or described.

In the accompanying drawings, forming a part of this specification, Figures 1, 2, and 3 are central vertical longitudinal sections of a car-coupler embodying my invention, showing the parts in different positions. Figs. 4 and 5 are detail side and rear views, respectively, of the lifting-piece; and Figs. 6 and 7 are detail side and rear views, respectively, of the lock.

In said drawings, A represents the forked draw-head of a car-coupler having the customary pivot-arm a, guard-arm a', and draw-bar a².

B is the knuckle; C, the pivot-pin; D, the gravity-lock; F, the lifting-piece; H, the lifting-lever, and h the chain connecting the same with the eye of the lifting-piece.

The gravity-lock D, which engages the tail b of the knuckle to hold the knuckle closed,

moves up and down in a guideway or passage a³ of the draw-head and is provided at its upper end with a hook d, which engages a corresponding hook f on the lower end of the lifting-piece. The lock D is furnished with a recess or chamber d' at its upper end to receive the hook f on the lifting-piece and permit a limited up-and-down movement of the lifting-piece in respect to the lock. The hook f has a strengthening-web f', and the rear wall or web of the lock D at the chamber portion thereof has a slot d² to receive said web f' when the lifting-piece is in its lowermost position in respect to the lock D, as shown in Fig. 1. The lock D has at its front side a shoulder or offset d³, adapted to rest upon the tail of the knuckle, and thus set the lock for uncoupling the couplers, as illustrated in Fig. 2, when the cars subsequently separate. The lock D has at its lower end a shoulder or offset d⁴, adapted to rest upon the lower web or floor a⁴ of the draw-head and support the lock in its raised position, and thus set the lock for automatically coupling the couplers when the cars subsequently come together. The lock-set leg d⁵ of the lock, which has the lock-set shoulder d⁴, is provided at its lower end with a guide finger or extension d⁶, which fits in the opening a⁵ in the lower web of the draw-head and serves as a guide to keep the lock in position when the lock is raised. The hook d at the front side of the upper end of the lock has a rounded shoulder d⁷, which engages a shoulder a⁶ on the draw-head at the front side of the lock passage-way therein and serves to prevent the lock from creeping and accidentally jumping upward when the cars are in motion. This will be readily understood from Fig. 1 of the drawings. The lifting-piece F has a toe or projection f² just above the hook f, which toe or projection f² is furnished with a curved or inclined upper face f³, and which toe or projection by engagement with the rear wall a⁷ of the lock passage-way in the draw-head holds the upper end of the lock in its forward position, as shown in Fig. 1, and the upper end of the lock or its shoulder d⁷ in proper engagement with the shoulder a⁶ on the draw-head, so that the lock cannot creep or jump upward when the cars are in motion. To aid

in this function, the rear wall of the lock passage-way in the draw-head has an incline or projection a^8 , and the socket or recess d' in the upper end of the lock which receives the hook f' of the lifting-piece is shaped to fit somewhat snugly at the lower portion thereof. The toe or projection f^2 on the lifting-piece by engagement with the cross-pin G , which extends through the draw-head at the side of the lock passage-way therein, also prevents the lock and lifting-piece from being entirely removed from the draw-head except by first removing this pin. The lifting-piece F is further provided at its upper end with a head f^4 , having a curved flange f^5 to fit over and close the lock passage-way in the draw-head. f^6 is the eye at the upper end of the lifting-piece for connection with the lifting-chain h . The head f^4 at the upper end of the lifting-piece has a curved or inclined lower face f^7 , and the lifting-piece has a cut-away portion or open space f^8 between the head f^4 and the toe or projection f^2 , which serves to facilitate the upward movement of the lifting-piece and lock and to prevent the same from binding under strain from the lifting-chain at different angles due to different positions of the coupler in respect to the car. The incline a^8 on the rear wall of the draw-head also facilitates the easy upward movement of the lifting-piece, especially under strains from the chain in a forward direction. As the hook d at the upper end of the lock is at the front side thereof or adjacent to the lock-set shoulders d^3 and d^4 when the lock is lifted by the hook on the lifting-piece, it automatically or by gravity tilts forward, as illustrated in Figs. 2 and 3, so that the shoulder d^3 will properly engage and rest upon the tail of the knuckle if the knuckle is closed, and thus automatically set the lock for uncoupling, or so that the shoulder d^4 will engage the lower web or floor of the draw-head, and thus set the lock in position for coupling if the knuckle is open.

45 I claim—

1. In a car-coupler, the combination with a forked draw-head and a pivoted knuckle, of a gravity-lock having a hook at its upper end at the front side thereof, and a lifting-piece 50 having a hook at its lower end engaging the hook on the lock, the draw-head having a shoulder at the front side of the lock passage-way therein engaging the upper end of the lock to prevent the lock from creeping or 55 jumping upward, substantially as specified.

2. In a car-coupler, the combination with a forked draw-head and a pivoted knuckle, of a gravity-lock having a hook at its upper end at the front side thereof, and a lifting-piece 60 having a hook at its lower end engaging the hook on the lock, the draw-head having a shoulder at the front side of the lock passage-way therein engaging the upper end of the lock to prevent the lock from creeping or 65 jumping upward, said lock having a socket or recess in its upper end to receive the hook on the lifting-piece, substantially as specified.

3. In a car-coupler, the combination with a forked draw-head and a pivoted knuckle, of a gravity-lock having a hook at its upper end 70 at the front side thereof, and a lifting-piece having a hook at its lower end engaging the hook on the lock, the draw-head having a shoulder at the front side of the lock passage-way therein engaging the upper end of the 75 lock to prevent the lock from creeping or jumping upward, said lock having a socket or recess in its upper end to receive the hook on the lifting-piece, and said socket or recess in the lock permitting a limited up-and-down 80 movement of the lifting-piece in respect to the lock, substantially as specified.

4. In a car-coupler, the combination with a forked draw-head and pivoted knuckle, of a lock having at its front side a lock-set shoulder adapted to engage the tail of the knuckle 85 to set the lock for uncoupling and a second lock-set shoulder adapted to engage the lower web or floor of the draw-head to set the lock for coupling, and a lifting-piece connected 90 with the lock at the front side thereof to cause the lock to tilt forward at its lower end when lifted and throw its lock-set shoulders into proper position for engagement, substantially as specified.

5. In a car-coupler, the combination with a forked draw-head and pivoted knuckle, of a lock having at its front side a lock-set shoulder adapted to engage the tail of the knuckle to set the lock for uncoupling and a second 100 lock-set shoulder adapted to engage the lower web or floor of the draw-head to set the lock for coupling, and a lifting-piece connected with the lock at the front side thereof to cause the lock to tilt forward at its lower end when 105 lifted and throw its lock-set shoulders into proper position for engagement, the draw-head having a shoulder engaging the front upper end of the lock to prevent the lock from creeping, substantially as specified.

6. In a car-coupler, the combination with a forked draw-head and pivoted knuckle, of a lock having at its front side a lock-set shoulder adapted to engage the tail of the knuckle to set the lock for uncoupling and a second 115 lock-set shoulder adapted to engage the lower web or floor of the draw-head to set the lock for coupling, and a lifting-piece connected with the lock at the front side thereof to cause the lock to tilt forward at its lower end when 120 lifted, and throw its lock-set shoulders into proper position for engagement, the draw-head having a shoulder engaging the front upper end of the lock to prevent the lock from creeping, said lifting-piece having a toe or 125 projection at its lower end engaging the rear wall of the lock passage-way in the draw-head to hold the upper front end of the lock in engagement with said shoulder on the draw-head, substantially as specified.

7. In a car-coupler, the combination with a forked draw-head and pivoted knuckle, of a lock having at its front side a lock-set shoulder adapted to engage the tail of the knuckle 130

- to set the lock for uncoupling and a second lock-set shoulder adapted to engage the lower web or floor of the draw-head to set the lock for coupling, a lifting-piece connected with 5 the lock at the front side thereof to cause the lock to tilt forward at its lower end when lifted, and throw its lock-set shoulders into proper position for engagement, the draw-head having a shoulder engaging the front 10 upper end of the lock to prevent the lock from creeping, said lifting-piece having a toe or projection at its lower end engaging the rear wall of the lock passage-way in the draw-head to hold the upper front end of the lock in engagement with said shoulder on the draw-head, and a pin extending across the rear side 15 of the lock passage-way in the draw-head and adapted to engage said toe or projection on the lifting-piece, substantially as specified.
- 20 8. In a car-coupler, the combination with a forked draw-head of a pivoted knuckle, a lock D, having hook d and recess d' in its upper end and provided with lock-set shoulders d^3 and d^4 , and a lifting-piece F having hook f at 25 its lower end, substantially as specified.
9. In a car-coupler, the combination with a forked draw-head, of a pivoted knuckle, a lock D, having a hook d and recess d' in its upper end and provided with lock-set shoulders d^3 30 and d^4 , and a lifting-piece F having hook f at its lower end and a toe or projection f^2 above said hook, substantially as specified.
10. In a car-coupler, the combination with a forked draw-head, of a pivoted knuckle, a lock D, having a hook d and recess d' in its upper end and provided with lock-set shoulders d^3 and d^4 , a lifting-piece F having hook f at 35 its lower end and a toe or projection f^2 above said hook furnished with a curved or 40 inclined upper face, substantially as specified.
11. In a car-coupler, the combination with

a forked draw-head, of a pivoted knuckle, a lock D, having hook d and recess d' in its upper end and provided with lock-set shoulders d^3 and d^4 , a lifting-piece F having hook f at 45 its lower end and a toe or projection f^2 above said hook, said lifting-piece also having a head f^4 at its upper end, substantially as specified.

12. In a car-coupler, the combination with a forked draw-head, of a pivoted knuckle, a lock D, having hook d and recess d' in its upper end and provided with lock-set shoulders d^3 and d^4 , a lifting-piece F having hook f at 50 its lower end and a toe or projection f^2 above said hook, said lifting-piece also having a head f^4 at its upper end and a cut-away portion between said head f^4 and said toe or projection f^2 , substantially as specified.

13. In a car-coupler, the combination with a forked draw-head, of a pivoted knuckle, a lock D, having a hook d and recess d' in its upper end and provided with lock-set shoulders d^3 and d^4 , a lifting-piece F having hook f at 55 its lower end and a toe or projection f^2 above said hook, and a cross-pin G, substantially as specified.

14. In a car-coupler, the combination with a forked draw-head, of a pivoted knuckle, a lock D, having a hook d and recess d' in its upper end and provided with lock-set shoulders d^3 and d^4 , a lifting-piece F having hook f at 60 its lower end and a toe or projection f^2 above said hook, said lifting-piece also having a head f^4 at its upper end and a cut-away portion between said head f^4 and said toe or projection f^2 , and a cross-pin G, substantially as specified.
